UNITED STATES PATENT OFFICE.

CASSIUS M. BARTHolemew, OF COLUMBUS, OHIO.

RING-TWIRLING TOY.

Application filed February 26, 1921. Serial No. 448,087.

To all whom it may concern:

Be it known that I, CASSIUS M. BARTHolemew, a citizen of the United States, residing at Columbus, in the county of Franklin 5 and State of Ohio, have invented a certain new and useful Improvement in Ring-Twirling Toys, of which the following is a specification.

The present invention relates to the type 10 of toy shown in the United States patent issued to me December 14, 1897, No. 595,594.

The principal object of the present invention is to do away with a spring and to utilize centrifugal action generated by pressing 15 sure of the fingers of the human hand to twirl and project the ring. Other objects will be gathered from the disclosure herein.

The invention is embodied in the example herein specifically shown and described, the 20 features of novelty being finally pointed out in the claims.

In the accompanying drawing—

Figure 1 is a side view of the shaft.

Fig. 2 is a similar view of one of the centrifugal members.

Fig. 3 is a plan view of the ring to be projected and twirled by the centrifugal members.

Fig. 4 is a perspective view of a clip that 30 may be placed on the finger to aid in manipulating the shaft.

Fig. 5 is a side view illustrating the parts of the toy assembled for operation.

Fig. 6 illustrates how the shaft is best initially placed between the finger and thumb for operation, the shaft being shown in cross section.

In the views 7 designates the shaft which is a short strip of wood having its upper end 40 diagonally cross sawed to provide slits 8 the lower ends of said slits being drilled to slightly enlarge them as shown at 8°.

The character 9 designates the centrifugal element, the body of which is a block of 45 wood recessed at its upper end, as shown at

10 sufficiently to straddle the shaft edge-wise. The block has passed through it a metal pin 11 bridging the recess 10 at its upper portion, said pin being of a slightly 50 greater diameter than the diameter of the saw cut 8 but so as to be capable of freely turning in the enlargement 8°. To connect the centrifugal element with the shaft the pin 11 is forced down through the saw cut 55 8, the outer part of the wood of the shaft beyond the saw cut springing slightly to

permit this. When so connected the centrifugal element cannot become accidentally removed.

The shaft is provided with two of the 60 centrifugal elements 9 as shown in Fig. 5, the recess in the upper end of such element being of such length and the pin 11 being so positioned that the elements rest against the shaft about as shown in Fig. 5. In this position the ring 12 to be twirled is placed on the centrifugal elements.

To operate the toy it is well to provide the middle finger of the hand with a clip 13 as shown in Fig. 6, said clip preferably being of metal or other material having a hard 70 smooth surface. It is preferable to put the clip 13 upon the middle finger so that the forefinger can be used to aid in adjusting the shaft and holding it until ready for flip-

75 ping. In practice the device prepared as shown in Fig. 5 is best taken at its shaft between the thumb and the clip 13 as shown in Fig. 6. Now by a quick pressure of the thumb the shaft can be flipped to the position shown in broken lines in Fig. 6. This quick partial rotation of the shaft throws the centrifugal elements outward and projects the ring 12 into the air with a twirling motion.

When so projected and twirled in 80 a direction at an incline to the horizontal the ring 12 after reaching the limit of its travel outward tends, because of gyrostatic action, to return in the path of its outward flight. The ring should be of fairly shallow 85 cylindrical form and light material, as for example rather stiff paper. Upon return of the ring from its outward flight it may be caught upon the centrifugal elements in the manner similar to that set forth in my 90 former patent referred to and the projecting and twirling operation repeated.

The forms of the parts can be changed 95 without departing from the gist of the invention as claimed.

What I claim is:

1. A ring projecting and twirling device comprising, in combination, a flat shaft adapted to be flipped between the thumb and finger of the human hand to partially 105 rotate the same, and a pair of ring supporting elements each loosely pivoted at one of its ends to the end of said shaft and adapted to be whirled and thrown upward at their free ends when the shaft is flipped as stated. 110

2. A ring projecting and twirling toy including, in combination, a shaft consisting

of a flat strip adapted to be flipped between the thumb and finger of the human hand to partially rotate the same, said strip provided with diagonally and opposingly located slits at one end, and a pair of ring supporting centrifugal elements each having a cross pin at one of its ends to pivotally engage said slits, substantially as described.

3. A ring projecting and twirling toy including, in combination, a shaft, a pair of 10 ring receiving centrifugal elements loosely attached thereto and a finger clip against which said shaft may be flipped to partially rotate the same, substantially as described.

CASSIUS M. BARTHOLOMEW.
